DUPLICATING MACHINE

Frank Chesley, Cincinnati, Ohio

Application December 2, 1933, Serial No. 700,693

7 Claims. (Cl. 101—131)

This invention relates to duplicating machines and is particularly directed to a machine of the character disclosed in the patent to Frank Chesley, No. 1,835,931, granted December 8, 1931. In 5 this patent a duplicating machine is disclosed in which a minimum sized conveniently applied printing blanket or flexible sheet is used, the printing blanket being drawn tautly across the surface of the platen by tensioning devices which 10 hold the blanket flat on the platen.

It is the object of the present invention to improve the machine disclosed in the aforesaid patent by the provision of a device for supporting the machine angularly or inclined relative to the table or supporting surface, whereby it is more convenient for the operator to apply the sheets to be printed thereon since the printing surface is tipped toward the operator.

It is a further object of this invention to provide a rack for the roll device used in applying the sheets of paper during the printing operation, which rack conveniently receives the roll device and is of particular utility in connection with the machine as supported in tipped or inclined 25 position.

It is a still further object of this invention to provide a paper aligning device through the medium of which the operator can quickly apply the paper on the printing blanket in correct position without difficulty and by the arrangement and construction of which it is possible to conveniently and quickly remove the sheets after 30 printing.

Other objects and further advantages will be 35 more fully apparent from a description of the accompanying drawing, in which:

Figure 1 is a perspective view of the improved 40 duplicating machine, showing it set up ready for use and showing the printing roll mounted in its supporting rack or bracket.

Figure 2 is a perspective view looking at the 45 under side of the machine and showing the supporting rack thereof in position out of use in full lines and showing the position of use in dotted lines.

Figure 3 is a sectional view taken on line 3—3, Figure 2.

The machine incorporating the present improvements described in general comprises a table 50 6 having a platen 7 on its surface, tensioning devices 8, 8, one mounted at each end of the table, and a printing blanket 9 disposed over the surface of the platen and secured at its respective ends in the attaching devices for drawing the sheet tautly over the platen.

Referring specifically to the details of the drawing, the table 6 provides a leg 10 at each corner thereof, a rubber button or cushion 11 being secured to the under side of each leg for preventing contact of the metal of the table with the surface upon which the device is placed. The table presents a smooth top upon which a layer of felt, constituting the platen 7, is secured. Each tensioning device comprises a bar 13 having upwardly extending hooks 14 formed integrally therewith at each end, these hooks being outwardly disposed relative to the table. 10

The bar 13 is mounted transversely across the end of the table, well down below the surface thereof, by means of studs 15, one secured in each end of the bar, these studs extending through the end wall of the table and having threaded ends upon each of which a nut 16 and washer 17 are secured. A tapered coil compression spring 18, surrounding each stud, is disposed between the bar and the wall of the table. The bores 19 through which the studs extend are of greater diameter than the studs, permitting rocking or canting of the studs relative thereto. This rocking takes place between the nuts and 25 the washers and is a vertical movement permitting the hooks to be pressed inwardly against spring pressure.

The printing blanket 9 is a standardized product embodying a layer of gelatin treated with 30 glycerine disposed on a fabric backing. A hem 20 is provided at each end of the blanket being formed by overlapping the fabric and stitching the same. A rod 21 is inserted in each hem, these rods or spindles extending from the ends 35 of the hems as at 22.

The hooks of the tensioning devices are sufficiently spaced apart to permit the width of the blanket and length of hem to be disposed therebetween and the spindles or rods to engage the 40 hooks. The blanket is placed in position by hooking the spindles at one end thereof in the respective hooks, drawing the blanket tautly across the surface of the platen and forcing the tensioning device at the opposite end of the machine inwardly, tipping the hooks with the thumb of each hand, while the forefinger of each hand engages the spindles and forces them over the hook edges. 45

The spindles are spaced apart a suitable distance for causing a slight tipping of the tensioning devices when the blanket is in position, this placing the blanket under spring tension at all times, whereby it is tautly engaged over the surface of the platen, the position of the hooks below 50 55

the surface of the table aiding in the proper dis-
position of the blanket on the platen.

In accordance with the present invention, a
5 guide 23 is provided for facilitating application
of the sheets to be printed to the printing blanket.
This guide is formed from a strip of angle iron
and is fastened to the top of the table along the
10 side edge of the platen by means of screws 24.
The guide extends substantially the length of the
table and its upstanding flange 25 provides a side
abutment against which the paper can be placed
15 laterally. This upstanding flange is cut away
as at 26 at the lower end of the guide or at the
end nearest the operator, and the attaching
flange is turned up at its end to provide a
20 lower edge abutment 27 against which the lower
edge of the sheet may be placed.

The attaching flange is also cut away adjacent
the side flange as at 28 to provide a clearance
25 wherein the operator can insert the finger or
fingernail for lifting the sheet.

Through the medium of this guide strip, both
a side stop and a bottom stop are incorporated.
25 The operator can quickly and conveniently place
the sheets accurately in position by engaging the
side edge of the sheet against the side abutment
and the lower edge against the lower edge abut-
ment and therefore drop the sheet into position on
30 the platen.

30 An adjustable stand or tilting device 29 is in-
corporated in the machine which can be readily
thrown from folded position of non-use against
the under side of the machine to a position of
35 use. Without the present device the machine
rests horizontally on the supporting surface.
With the machine in this position it is difficult
however and inconvenient for the operator to
apply the sheets to be printed, particularly when
40 the operator is seated at a table. To overcome
this and to make the machine much less awk-
ward to use, the stand 29 has been incorporated
which materially raises the outer end of the
machine or the end farthest away from the
45 operator, and places the platen and printing
blanket more uniformly closer to the operator.
This stand or adjustable supporting device con-
sists of a rod bent to U-shape having outwardly
turned pivot portions 30 supported in lugs 31 de-
50 pending from the under side of the body of the
machine.

55 The cross piece 32 of the U-shaped element has
rubber sleeves 33 fixed thereon toward the legs
thereof for a non-slip contact with the table
on which the machine is supported. A clip 34
is fixed to the under side of the machine centrally
60 thereof and includes a spring metal extension
having a depression for receiving the cross piece
of the bracket or stand and an outwardly flared
end. The bracket engaging the outwardly flared
end cams the clip and forces it back permitting
65 the rack to slip into the depressed portion thereof.

70 This clip then holds the bracket in dismounted
position against the under side of the machine.
When it is desirable to use the supporting stand
65 or bracket it is swung rearwardly and its legs
engage the back wall or flange 35 of the body of
the machine as shown in Figure 1. With the ma-
chine in this inclined position, it is much easier
to operate the machine and a greater production
75 is assured.

75 As adjunct to the machine, a roller tool 36 is
provided. This tool includes a rubber roll 37
substantially the same in length as the blanket is
in width. The operating handle for the roller
75 consists of a U-shaped clip 38 with a gripping

member 39 extending medially and laterally from
the clip. This roll is worked up and down the
sheets of paper as they are applied to the printing
blanket and if left on the blanket will roll off
the end thereof.

5 A receptacle or trough 40 for holding the roll
device is provided at the lower end of the ma-
chine. This trough is in the nature of a channel
element disposed crosswise at the lower end of the
table of the machine, its attaching flange 41 10
lying against the inner side of the cross bar of one
of the tensioning devices. The studs of the ten-
sioning devices traverse slots 42 in the attaching
flange and the springs 43 therefor engage be-
15 tween this flange and the body of the machine
for holding the attaching flange rigidly against
the cross bar.

The outer upstanding flange 43 of the trough
is of sufficient height to block and divert the roll
20 device into position in the trough as it is brought
off the lower end of the printing blanket follow-
ing the printing of a sheet.

More specifically, in operation the drawing or
printing to be copied is drawn upon an original
25 using the proper ink or writing instrumentality
which will be readily transferable to the surface
of the blanket. This original is placed with the
inscribed face down upon the blanket. The roll
device is moved up and down over the sheet caus-
30 ing adherence to the blanket. The original is
then stripped from the blanket and the writing
or drawing has been transferred to the gelatin
surface. Thereupon sheets are successively
35 placed against the surface of the printing sheet
and accurately located by using the guide. The
roll device is used for rolling each printing and is
dropped conveniently into the tray as it is brought
40 off the lower end of the printing blanket.

Inasmuch as it will require a considerable
45 number of hours for the data on the printing
blanket to penetrate the layer of compound, the
blanket may be removed and replaced by a fresh
blanket. Successive blankets may be used and
in the end the first used blankets will be recon-
45 ditioned by the absorption of the printing into
the layer.

Having described my invention, I claim:

1. In a duplicating machine, a table, a print-
ing element mounted on said table, an adjust-
able stand for said table pivoted at the rear end
50 thereof, said table including a downwardly ex-
tending flange at its rear end, and said stand en-
gaging said flange for limiting rearward swing-
ing movement of the stand, whereby the stand
55 supports the rear end of the machine in elevated
position.

2. In a duplicating machine, a table having a
printing surface, a swinging stand for said table
pivoted at one end thereof, an abutment for said
stand for limiting outward swinging movement
60 thereof and disposing the stand in support po-
sition, whereby the stand elevates the end of the
machine, and means for securing the stand
against the under side of the table.

3. In a duplicating machine, a body incor-
porating a printing table and depending side
flanges and legs, and a U-shaped stand element
having lateral end extensions pivotally mounted
65 in the sides of the table from the inner side there-
of, said stand adapted to engage the rear flange
of the table for limiting rearward swinging move-
ment of the stand and supporting the table in
inclined position.

4. In a duplicating machine, a body incor-
porating a printing table, a stand element for sup-
75

porting the table in inclined position, a roller device, and a supporting trough for said roller device mounted on the body below the forward end of the table and disposed crosswise for receiving the roller device as it is brought off the surface of the printing table.

5. In a duplicating machine, a frame incorporating a printing table, a channel shaped receptacle secured to the table below the surface thereof and at one end, said receptacle disposed crosswise for receiving a roller device operating back and forth along the printing surface of the table.

10. In a duplicating machine, a frame incorporating a printing table, means for tilting said frame toward the operator, a channel shaped receptacle secured to the lower end of the table

below the surface thereof, said receptacle disposed crosswise for receiving an elongated roller device lengthwise thereof as it is moved from the printing surface of the table.

15. In a duplicating machine, a frame incorporating a printing table, an angle iron guide strip secured along one side edge of the table and providing an upstanding side abutment flange lengthwise of the table, and an upstanding end abutment flange at one end of the table, said side flange cut away adjacent the last mentioned flange, said angle iron guide strip providing an attaching flange cut away adjacent the cut-away portion of the side flange, whereby the finger may be inserted under the paper as it lies against the 20 respective flanges and upon the printing table.

FRANK CHESLEY.
